US00D478282S

(12) **United States Design Patent** (10) Patent No.: **US D478,282 S**
 Hayes et al. (45) Date of Patent: **** Aug. 12, 2003**

(54) **SMOOTHWALL CONTAINER**

(75) Inventors: **Thomas J. Hayes**, McHenry, IL (US);
Brian J. Cammarata, Farmington, NY (US); **William J. Loiselle**, Lindenhurst, IL (US)

(73) Assignee: **Pactiv Corporation**, Lake Forest, IL (US)

(**) Term: **14 Years**

(21) Appl. No.: **29/167,459**

(22) Filed: **Sep. 13, 2002**

(51) LOC (7) Cl. **09-03**

(52) U.S. Cl. **D9/425**; D3/307

(58) Field of Search D9/420-426, 432, D9/337; D7/629, 601; 206/505, 518, 216, 541, 521, 523; 220/556, 315, 780, 784, 793, 4.21-4.27, 790, 791, 801, 805, 259, 263, 836, 837; 229/406, 407, 902, 938; 426/107, 109, 113, 120; D3/304, 307

(57) **CLAIM**

The ornamental design for “smoothwall container”, substantially as shown and described.

DESCRIPTION

FIG. 1 is a perspective view of the container according to one embodiment of the present invention.

FIG. 2 is top view of the container of FIG. 1.

FIG. 3 is a bottom view of the container of FIG. 1.

FIG. 4 is a front view of the container of FIG. 1.

FIG. 5 is a back view of the container of FIG. 1.

FIG. 6 is an end view of the container of FIG. 1; and,

FIG. 7 is the other end view of the container of FIG. 1.

1 Claim, 7 Drawing Sheets
